(57) **CLAIM**

We claim the ornamental design for a cap, as shown and described.

DESCRIPTION

FIG. 1 is a front perspective view from top and front;

FIG. 2 is a front view;

FIG. 3 is a back view;

FIG. 4 is a left side view;

FIG. 5 is a right side view;

FIG. 6 is a top view; and,

FIG. 7 is a bottom view.

In the drawings, the broken lines show portions of a cap that form no part of the claim.

1 Claim, 2 Drawing Sheets
